UNITED STATES PATENT OFFICE.

MICHAEL SHIRES AND JOHN QUINCY ADAMS KENNEDY, OF CENTRE HALL,
PENNSYLVANIA.

FIRE-ESCAPE.

SPECIFICATION forming part of Letters Patent No. 374,633, dated December 13, 1887.

Application filed August 27, 1887. Serial No. 248,067. (No model.)

To all whom it may concern:

Be it known that we, MICHAEL SHIRES and JOHN QUINCY ADAMS KENNEDY, citizens of the United States, residing at Centre Hall, in the 5 county of Centre and State of Pennsylvania, have invented new and useful Improvements in Fire-Escapes, of which the following is a specification.

Our invention relates to improvements in 10 fire-escapes; and it consists in a certain novel construction and arrangement of parts for service, fully set forth hereinafter, and specifically pointed out in the appended claims.

In the drawings, Figure 1 is a view of our 15 device attached to a house. Fig. 2 is a detail view of the device detached. Fig. 3 is a transverse sectional view with the case closed. Fig. 4 is a detail view showing the joint between the rounds and the wires. Fig. 5 is a detail 20 view of one of the rounds.

Referring by letter to the drawings, A designates a case secured to the side of the house under the window, having a hinged lid, B, adapted to close over the case and exclude the 25 rain and dust.

C designates a cylinder or drum journaled in the ends of the case and adapted to be removed at will therefrom, and the said drum is provided on one side with a series of hooks, c 30 c, for a purpose hereinafter explained. There is also a series of hooks, D D, on the side of the house directly under the window and above the case A, to which hooks is secured the upper end of the ladder.

G designates the ladder, comprising the suspending-wires H, which consist of two or more strands twisted together, and the rounds I, provided with notches on the opposite sides at the points where the suspending-wires cross 40 them. The strands of the suspending-wires are separated at intervals and the rounds passed through the loops thus formed, the said strands being secured in the notches formed in the sides of the rounds. It will now be readily seen that when weight is put upon the ladder the strain upon the suspending-wires will only tend to hold the rounds more tightly in place, and there will be no chance for the same to slip.

K designates rings secured to each end of the ladder, which are adapted to be engaged

by the hooks on the side of the house or by the hooks on the drum or cylinder.

The manner of operating the fire escape is as follows: One end of the ladder, which we 55 will designate L, is attached to the house by means of the rings and hooks, and the other end, M, is attached to the roller or drum. When the occupant of the room desires to descend to the ground, he lifts the said drum, around 60 which the ladder is wound, from its bearings and throws it down toward the ground. The weight of the cylinder is sufficient to carry the lower end of the ladder down as far as possible. The occupant of the room now descends 65 in the ordinary manner. In case the house does not entirely burn down and it is desired to return the escape to its case, the cylinder is removed from the lower end of the ladder and replaced in its bearings in the case, and the 70 upper end of the ladder, L, is engaged thereto, while the lower end, M, still hangs to the ground. A crank is now applied to one side of the drum and the ladder rerolled thereon, after which the end M is attached to the hooks 75 on the house. This manner of returning the ladder to its case is very simple and easy of accomplishment.

This fire-escape will be found very convenient and efficient. While not in use it is safely 80 stored in the case, and when desired for use it is readily thrown from its case, and it immediately drops into its operative position. As it is ordinarily inclosed in the case, it will not serve as a means of entrance to thieves, who 85 might take advantage of the ladder were it normally extended to the ground.

The ladder being metallic, and consequently elastic, is very liable to cause the drum or cylinder to revolve and partly unroll the ladder, 90 and to prevent this we arrange a cleat or bracket, N, on the inner side of the case at one end, and secure a pin, O, in a socket in the end of the said drum, so as to engage the said bracket and prevent the turning of the cylinder. When it is desired to use the ladder, the pin is withdrawn, and the cylinder will then revolve. As an additional safeguard against the rounds slipping out of place, we provide them on the ends with rounded projections or 95 balls i i, or, if preferred, T-shaped heads.

As before stated, the object in having the

cylinder attached to the lower end of the ladder in the operative position is to carry the ladder down properly and stretch it, and also to prevent the lower end of the ladder from 5 engaging in projections or irregular surfaces.

Having thus described our invention, we claim—

1. In a fire escape, the combination, with the case A, having bearings in the ends, and the 10 hooks D D above the said case, of the cylinder or drum C, journaled in the bearings in the case and having the hooks c c on the side thereof, and the ladder G, comprising the suspending wires or ropes H and the rounds I, 15 secured thereto and having the rings K secured to each end thereof, the rings at one end of the ladder being adapted to be engaged over the hooks D and the rings at the other end over the hooks c, substantially as and for the 20 purpose specified.
2. In a fire-escape, the combination, with the case secured to the side of the house, of the cylinder or drum journaled therein and the 25 flexible ladder G, adapted to be wound on the drum, with one end secured removably thereto and the other end secured removably to the house, the positions of said ends being reversible at will, substantially as and for the purpose specified.
3. In a fire-escape, the combination, with the 30 case A and the hooks D D above the same, of

the cylinder journaled in the case and having hooks c c on one side, and the ladder G, having hooks or rings K K on the opposite ends to engage with the hooks D and c, respectively, 35 the said ladder comprising the suspending wires H H, consisting of strands of wire twisted together, and the rounds I I, provided in opposite sides with notches, the strands of the wire being adapted to be separated, the rounds 40 placed in the loops thus formed, and the strands engaged in the said notches, all constructed and arranged substantially as and for the purpose specified.

4. In a fire-escape, the combination of the 45 case A, having the bracket or cleat thereon at the end, the cylinder or drum journaled in the case and having a socket in the end, the ladder secured to and adapted to be reeled on the drum, and the pin O, adapted to be secured in 50 the said socket and engage the bracket to prevent the drum from turning when the ladder is reeled thereon, all substantially as and for the purpose specified.

In testimony that we claim the foregoing as 55 our own we have hereto affixed our signatures in presence of two witnesses.

MICHAEL SHIRES.

JOHN QUINCY ADAMS KENNEDY.
